[57] CLAIM

The ornamental design for a solar powered insect killer, as shown and described.

DESCRIPTION

FIG. 1 is a front, top, and side perspective view of a solar powered insect killer, showing my new design; FIG. 2 is a front elevational view thereof; the rear being substantially the same;

FIG. 3 is a left side elevational view, the right side being a mirror image thereof;

FIG. 4 is a top plan view thereof; and,

FIG. 5 is a bottom view thereof.

FIG.1.

FIG. 4.

FIG. 2.

FIG. 5.

FIG. 3.
